CIRCUIT BREAKER

Ture Lindstrom, Edgewood, and Jerome Sandin,
 Forest Hills, Pa., assignors to Westinghouse
 Electric & Manufacturing Company, East
 Pittsburgh, Pa., a corporation of Pennsylvania

Application July 10, 1941, Serial No. 401,690

12 Claims. (Cl. 200—89)

The invention relates to circuit breakers of the type embodying an operating mechanism which is manually operable to open and close the circuit and automatically operable to open the circuit in response to predetermined conditions. The present invention constitutes an improvement over the circuit breaker mechanism disclosed in Patent 2,083,304 issued to Ture Lindstrom, June 8, 1937, and assigned to the assignee of this invention.

An object of the invention is the provision of a manually and automatically operable circuit breaker with an improved means for preventing the holding of the circuit closed during the existence of an overload circuit condition.

Another object of the invention is the provision of a circuit breaker with an improved means for preventing reclosing of the circuit by improper manipulation of the operating handle following an automatic opening operation of the circuit breaker.

Another object of the invention is the provision of a manually and automatically operable circuit breaker with an improved means for preventing reclosing movement of the contacts when the handle is held in closed position during and following an automatic opening operation of the breaker.

Another object of the invention is the provision of a manually and automatically operable circuit breaker with an improved latching means for holding the contacts in open position after automatic opening thereof until the operating handle has been properly operated to reset and reclose the circuit breaker.

Another object of the invention is the provision of a circuit breaker with an improved holding, or latching means as previously described and wherein the latching means is jointly controllable by the circuit breaker operating mechanism and the handle.

Another object of the invention is the provision of a manually and automatically operable circuit breaker with a pair of latches disposed side by side and engageable with the same element of the mechanism, one serving to hold the contacts in full open position after automatic opening thereof until the handle is properly operated to reset and reclose the breaker and the other to hold the contacts in open position until the main operating spring has been given a maximum operating stress and at this point to release the mechanism so that the contacts will be closed quickly and positively.

Another object of the invention is the pro-

vision of a circuit breaker as previously described that is simple, compact, reliable in operation, and inexpensive to manufacture.

The novel features that are considered characteristic of the invention are set forth in particular in the appended claims, the invention itself, however, both as to structure and operation, together with additional objects and advantages thereof, will be best understood from the following detailed description of several embodiments thereof when read in conjunction with the accompanying drawings, in which:

Fig. 1 is a front elevational view of a three-pole circuit breaker embodying the principal elements of the invention. The cover has been partly broken away to more clearly show some of the parts of the circuit breaker;

Fig. 2 is a vertical sectional view of the circuit breaker taken substantially on line II—II of Fig. 1 and looking in the direction of the arrows;

Fig. 3 is an enlarged detail view, partly in section, of the circuit breaker mechanism and the contact structure in the closed position thereof. Some of the parts have been broken away more clearly to show the structure;

Fig. 4 is an enlarged detail view similar to Fig. 3, showing, the breaker mechanism and the contact structure in the tripped open position;

Fig. 5 is an enlarged detail view similar to Fig. 3, showing the circuit breaker mechanism and the contact structure in the manually opened position;

Fig. 6 is an enlarged detail view similar to Fig. 3 showing the circuit breaker mechanism and the contact structure in the tripped open position but with the operating handle held in closed position;

Fig. 7 is a perspective view of the circuit breaker operating mechanism and a part of the contact structure;

Fig. 8 is a front elevational view of a part of the latching mechanism; and

Fig. 9 is a detail view of a part of the operating mechanism showing a modified form of one of the latches.

Referring to the drawings, a base 1 of moulded insulating material has mounted thereon six terminals 3 and 5, a trip device 7, an operating mechanism 9 with its associated assemblage of switch members 11, the arc extinguisher 13, and three stationary contact assemblages 15. The movable contact assemblages 11 and the three stationary contact assemblages 15 combine to form a plurality of poles. Each of the poles is

insulated from the adjacent pole by means of insulating barriers 17 (Figs. 1 and 2) moulded integral with the base 1. These barriers are in alignment with similar barriers 21 in a cover 19 also made of insulating material. An operating member 23 is provided with a handle 25 and is pivotally supported on the frame 41 of the operating mechanism 9. A suitable opening is provided in the cover 19 for the operating handle. The trip device 7 is secured in position by screws 31 and 33 which also serve to connect terminals 35 and 37 of the trip device, respectively, to flexible shunt conductors 39 and the terminals 5.

The electrical circuit for each of the poles is substantially the same and extends from the terminal 3 through the main stationary contact assemblage 15, the cooperating movable contact assemblage 11, the flexible shunt conductor 39, terminal 35, trip device 7 to the terminal 5.

The assemblage of switch-members 11 is pivoted to the frame 41 of the operating mechanism 9 by means of a pin 42. A metal tie-bar 43 rigidly connects the three switch assemblages 11 so that they pivot as a unit about the pin 42. Each of the switch members 11 is secured to the tie-bar 43 by means of a clamp 45 and a bolt 47. In order to prevent short circuiting the several poles the switch members 11 are insulated from the tie-bar 43 by an insulating tube 48 surrounding the tie-bar 43.

Each of the movable contact assemblages 11 includes a pair of contact members 52 supported on a pivot 53 carried by inwardly extending projections 54 of the clamp member 45. The contact members 52 are biased into engagement with contacts 56 of the stationary contact assemblage by springs 55. Projections 61 on rearwardly extending portions 60 of the contact members 52 are adapted to engage the projections 54 of the clamp member 45 to limit the counter-clockwise movement of the members 52 about their pivot 53.

The third contact member 49 (Figs. 2, 3, 4, 5 and 6) of the movable contact assemblage 11 is disposed between the outer contacts 52 and includes an arcing contact 50, a body portion 62 provided with a slot 63 (Figs. 3, 4, 5 and 6) and an intermediate contact 51. A rearwardly extending portion 64 of the body 62 is pivoted on the pin 53 and is conductively joined to the central portion of a flexible shunt conductor 39. The outer portions of the shunt conductor 39 are connected to the main contact members 52. A spring 66 compressed between the top of the portion 62 and a projection 67 of the clamp 45 provides the contact pressure for the contacts 50 and 51 which are adapted to engage cooperating contacts of the stationary contact means 15. A spring guide 68 passes through an opening in the projection 67 and has its lower end curved to lie within the slot 63 where it is connected to the contact arm 62 by means of a pin 69.

The clamp member 45 of the central switch member 11 has a bifurcated section 76 formed integral therewith which has openings for engaging the contact assemblage pivot pin 42, openings for engaging the breaker operating mechanism, and slotted openings 79 for clearing the pivot pin 80 of the operating member 23.

The limit of clockwise or opening movement of the assemblage of switch member 11 as they rotate about the common pivot 42 is defined by the engagement of a portion of the central clamp member 45 with portions 82 of the side walls of the frame 41 (see Figs. 4 and 5).

The arc extinguishers 13 may be of the spaced

plate type and are disposed adjacent the arc path, the plates being provided with slots of substantially the same outline as the moving contacts. The arc is moved into the spaces between the plates where it is rotated by a suitable means until it is cooled and extinguished. Patent 1,896,764, issued to M. W. Brainard on February 7, 1933, fully discloses and describes the structural features and operation of an arc extinguisher of this type.

The frame 41, which is secured to the base 1 by screws 90 and 91, supports the breaker operating mechanism 9. This mechanism includes pairs of toggle links 83 and 84, pivotally connected by a knee pin 94. The toggle link 83 comprises a pair of parallel links rigidly connected by a yoke 92, and the toggle link 84 also comprises a pair of parallel links rigidly connected by a yoke 95. The yoke 95 of the toggle link 84 is disposed to engage the underside of the yoke 92 of the toggle link 83 to limit the outward motion of the knee of the toggle.

The toggle link 83 is pivotally connected by means of a pin 93 to the portion 16 of the central clamp member 45 and thus to the three switch members 11. The ends of the parallel links forming the toggle link 84 are rounded as indicated at 104 (Fig. 7) to form bearings which engage suitable recesses in the upwardly extending arms 30 of a bell crank carrier 105 which is pivoted at its apex to the frame 41 by means of a pin 109. Retainer plates 106 (only one being shown) are secured to the outer faces of the bell crank lever 105 to prevent lateral displacement of the toggle link 84. These plates 106 are provided with openings into which project studs 107 in the bearing portions 104 of the toggle links 84 to prevent longitudinal displacement of the bearings from the bell crank 105. An overcenter spring 99 is tensioned between the knee pin 94 of the toggle and the operating member 23, the spring being threaded at one end onto a member 97 which is pivotally connected to the member 23 by a pin 100. At its opposite end, the spring 99 is threaded onto a member 98 pivoted on the knee pin 94 of the operating toggle. The spring 99 at all times exerts a tension force between the knee of the toggle 83-84 and the operating member 23.

The bell crank carrier lever 105 comprises a pair of parallel bell cranks 105 joined at their left hand ends (Fig. 3) by a cross bar or yoke 108. A latch member 111 comprising a pair of substantially parallel members 111 pivoted to the frame 41 by means of a pin 115 has a yoke 112 joining the two members 111 substantially above the pivot pin 115. In the normal position of the parts, the yoke 112 lies directly above and in the path of travel of the yoke 108 thus normally preventing clockwise travel of the bell crank carrier 105 under the influence of the spring 99. The latch member 111 is releasably retained in its normal latching position by a latch 114 of the trip device 7 and is provided with a latch engaging element 117 pivotally mounted on a yoke 113 joining the free ends of the latch members 111.

The latch member 111 is normally restrained in latching position by the trip device 7 which is responsive to predetermined overload conditions in the circuit of any of the poles of the breaker to release the member 111 and thereby cause automatic opening of the circuit breaker. The instant invention is not particularly concerned with the details of the trip device 7 as any suitable device possessing the proper characteristics

may be used, for instance, a trip device such as is disclosed in United States Patent 2,043,306, granted June 9, 1936 to Jerome Sandin and which is assigned to the assignee of the instant invention. Such a trip device includes a current responsive bimetal trip element and an electromagnetically responsive trip element electrically connected in each pole of the breaker, and a common trip bar operable by any one of the thermally or magnetically responsive trip elements to effect release of the circuit breaker latching lever 111.

Upon the occurrence of an overload of predetermined value in any one of the poles of the breaker, the current responsive bimetal element acts to trip the breaker mechanism after a predetermined time interval. If the overload in the circuit of any one of the poles is greater than a predetermined magnitude or is a short circuit, the electromagnetically responsive element in that pole acts to immediately trip the operating mechanism and open all the circuit breaker contacts substantially instantaneously. Suitable means are provided to restore all the parts of the trip device to operative condition following an operation.

The latch 119 (Figs. 3, 4, 5, 6 and 7) is provided to prevent the overcenter spring 99 from closing the switch member 11 until the operating handle has reached a predetermined point during the closing operation, that is, until the operating handle has been moved almost to the fully closed position so that the operating spring will be stretched substantially to the maximum length before the latch releases the switch member 11. This insures that the contacts will be closed quickly and positively. This latch comprises a pair of parallel members 119 (see Fig. 8) pivotally mounted by means of a pin 121 on the frame 41, and the latch is biased in a clockwise direction by a spring 125 having one end anchored to the latch and the other fast to a pin projecting from the frame 41. A roller 123 (Figs. 6 and 7) rotatably supported on a pin 124 connecting the members 119 is adapted to cooperate with the toggle pin 93 when the breaker mechanism is in the open position. The projecting free end 126 of the latch 119 engages the pin 93 of the toggle link 83 to limit clockwise movement of the latch. The latch is released by the engagement of a shoulder 127 (Fig. 4) on the underside of the operating member 23 with a tail 128 of the latch 119.

Another latch comprising a bifurcated member 129 is also pivoted on the stud 121. The purpose of this latch is to prevent the spring 99 from partially closing the switch member 11 and thus prevent any rebound of the contacts from the open position in the event that the handle 25 is held in the closed position when the breaker mechanism is tripped open by an overload current. The latch 129 is biased in a counter-clockwise direction toward latching position by a spring 131 (see Fig. 8) having one end anchored on a pin 133 on the latch and the other end secured to a pin on the frame 41. A cam face 130 on the upper fork of the latch 129 is adapted to cooperate with the operating member 23 and the lower fork is shouldered as at 136 (Fig. 4) to engage the toggle pin 93 in a manner to be more fully described later in connection with the description of the operation of the breaker.

When the breaker contacts are in their fully

closed position (Fig. 3) and an overload or short circuit occurs in the circuit controlled by any one of the poles, the latch lever 111 is released by the trip device 7. The latch lever 111 then moves 5 counter-clockwise (Fig. 3) about its pivot 115 under the influence of a spring 149 and also by a component of the force of the operating spring 99, one end of the spring 149 bearing on a projection 151 of the latch lever 111. At this movement 10 of the latch lever, the yoke 112 thereof is moved out of restraining relation with the yoke 108 of the carrier lever 105 freeing the latter for movement by the operating spring 99 which, acting 15 through the toggle link 84, immediately rocks the carrier lever 105 clockwise about its pivot 109. In this action, the spring 99 is assisted by the contact springs 55 and 66 acting through the switch members 11 and the toggle 83-84. During the opening operation, the line of action of 20 the operating spring 99 moves from a position above the center of the pivot pin 80 for the operating member 23 to a position below the pin 80. This biases the operating member 23 in a clockwise direction about the pin 80 and immediately 25 moves the operating member until it is arrested by engagement of rollers 137 with the surfaces 139 on the carrier member 105. The parts are shown in this position in Fig. 4. This position of the operating handle provides a convenient 30 means for indicating that the breaker has been automatically tripped open.

When the parts are in their fully closed positions (Fig. 3) a small clearance exists between a projection 147 on the switch arm 76 (seen in Figs. 35 4, 5 and 6) and the yoke 92 of the toggle link 83. Soon after the latch lever 111 frees the carrier lever 105 and the parts start their opening movement, the contact members 11 close this clearance and the projection 147 comes into contact 40 with the yoke 92. This causes clockwise movement of the knee pin 94 about the pivot pin 42 and changes the line of action of the resultant force exerted by the operating spring 99 so that the spring will tend to bias the knee of the toggle 45 inward toward collapsed position if the operating member 23 is permitted to move to the intermediate position shown in Fig. 4. When the toggle collapses, the parts are moved to the positions in 50 which they appear in Figure 4 in which the contacts are in the fully opened position.

To effect manual opening of the contacts the operating handle 25 (Fig. 3) is moved clockwise about the pivot 80. Shortly after the beginning of the clockwise movement, a projection 145 on the operating member 23 engages the yoke 92 of the toggle link 83 and upon continued movement of the handle positively moves the toggle 83-84 in the direction to cause collapse. At the same time, the movement of the operating member 23 55 moves the overcenter spring 99 across the center line of the toggle link 84 whereupon it exerts a downward pull on the knee pin 94 causing complete collapse of the toggle. This causes the contacts to open with a snap action. The parts are 60 shown in their manually opened position in Fig. 5.

The latch 119 (Figs. 3, 4, 5 and 6) is effective 70 to latch the movable switch members 11 in the open position whether the breaker is operated manually or tripped under the influence of an overload circuit condition. As soon as the pivot pin 93 of the toggle link 83 passes to the right of the roller 123 of the latch 119, the spring 125 rocks the latch clockwise into the path of the pin

93 to latch the movable contacts in the open position.

Following each opening of the circuit breaker in response to an overload circuit condition, it is necessary to restore the operating mechanism and the trip device to an operative condition. This is accomplished by moving the handle 25 from the position in which it is shown in Fig. 4 to the full open position in which it appears in Fig. 5. During this movement the rollers 137 on the operating member 23 engage the carrier 105 and move it counter-clockwise. As the carrier 105 nears the end of its counter-clockwise travel, the yoke 108 on the free end thereof engages a projection 155 (Fig. 3) forming a part of the yoke 112 of the latch lever 111 and rocks this lever clockwise. Near the end of the clockwise movement of the latch lever 111, the latch element 117 thereof reengages the latch 119 of the trip device 7 and at the same time the latch yoke 112 resumes its latching position in the path of the yoke 108.

When the breaker mechanism is in the open and reset position shown in Fig. 5, the line of action of the spring 99 is below the center line 94-107 and as a result the spring 99 restrains the toggle 83-84 in its collapsed position (Figs. 4 and 5), the clockwise or opening movement of the movable contact assemblage being limited by the central clamp member 45 striking the frame 41. In this position there is a slight clearance between the toggle pin 93 and the roller 123 of the latch 119.

To close the circuit breaker the handle 25 is rocked counter-clockwise to the closed position (Fig. 3). As the line of action of the spring 99 passes above the center line 94-107 the spring 99 biases the toggle 83-84 to its straightened position taking up the slight clearance between the pin 93 and the latch roller 123, and since the latch 119 occupies a latching position in the path of the toggle pin 93 the movable contacts are held in the open position while the counter-clockwise movement of the operating member 23 increases the tension of the spring 99. Near the end of the counter-clockwise travel of the handle 25, the shoulder 127 on the operating member 23 strikes the tail 128 and rocks the latch 119 counter-clockwise out of the path of the pin 93 whereupon the spring 99 acts to straighten the toggle 83-84, thus closing the contacts with a snap action.

When the contacts have been opened manually the latch 111 has not been tripped and the handle 25 occupies the position shown in Fig. 5. In this case the contacts may be closed by moving the handle 25 from the position in Fig. 5 to that shown in Fig. 3. The latch 119 functions in the above described manner to retain the parts in the open position and to release the movable contact means near the end of the closing movement of the handle 25.

Should an attempt be made to close the breaker against an overload or a short circuit condition, the latch lever 111 will again be released in the above described manner, after a predetermined time delay or instantaneously, depending on the magnitude of the overload current. The carrier lever 105 will also be released and will cause the mechanism to again break the toggle 83-84 and open the contacts. It is not possible, therefore, to hold the breaker against an overload circuit condition.

When the operating mechanism 23 is in the closed position, the previously mentioned cam

face 130 of the latch 129 is disposed just below a recess 135 in the operating member 23 and is held in unlatched position by the toggle pin 93 in the fork of the latch. When the breaker is opened either manually or automatically, the pin 93 is withdrawn from the fork of the latch 129 to the position shown in Figs. 4 and 5. At the same time, the clockwise movement of the operating member 23 has moved the recess 135 toward the right from above the cam face 130, and a projection 148 on the underside of the member 23 holds the latch 129 in its lower or ineffective position. At the beginning of the counter-clockwise or closing movement of the operating member 23, the toggle pin 93, under the influence of the spring 99 moves toward the left into contact with the roller 123 on the latch 119 where it is restrained until near the end of the manual closing operation of the operating member when the shoulder 127 strikes the tail 128 and disengages the latch 119. Since the shouldered portion 136 of the latch 129 is longer than the latch 119, it can be seen that the latch 129 will be held out of the path of the pin 93 and will not be effective to restrain the operating mechanism on normal operations.

Referring now to Fig. 6, if the breaker should be automatically tripped while the handle 25 and the operating member 23 are held in the closed position, the latch 119, due to the engagement of the shoulder 127 with the tail 128, is held in its ineffective or unlatched position. However, as soon as the toggle 83-84 collapses and moves the toggle pin 93 clear of the shoulder 136, the latch spring 131 rocks the latch 129 counter-clockwise interposing the shoulder 136 in the path of the toggle pin 93, thus preventing rebound of the contact arm 76 from the open position toward closed position. At this movement of the latch 129, the cam portion 130 enters the recess 135. Without the latch 129 the spring 99 would tend to move the contacts towards closed position should the handle be held in closed position when the breaker trips, as can be seen in Fig. 6 since in this position the line of action of the spring is above the pivot 107.

The parts will remain in the position shown in Fig. 6 until the handle is released and moves clockwise to its Fig. 4 position. During the early part of the clockwise movement of the handle the shoulder 127 on the operating member 23 moves away from the tail 128, permitting the spring 125 to rock the latch 119 into the path of the toggle pin 93. Slightly later in the clockwise movement of the handle, the projection 148 engages the cam portion 130 and rocks the latch 129 clockwise, moving the shoulder 136 out of the path of the toggle pin 93.

The manual clockwise movement of the handle 25 from its Fig. 4 position to its Fig. 5 position resets the operating mechanism and reengages the latch member 117 with the trip device as previously described. The handle 25 is then moved counter-clockwise to its closed position, the shoulder 127, near the end of its travel, rocking the latch 119 to permit the spring 99 to re-close the contacts.

Should the handle 25 be moved from the tripped open position (Fig. 4) to the closed position (Fig. 3) without first moving the handle to the open position (Fig. 5) to reset the mechanism, the latch 119 would be moved to its unlatched position when the shoulder 127 strikes the tail 128 of the latch. The latch 129 is ineffective to restrain the contacts in open position until the

handle is near its closed position, consequently the contacts will be moved to partly closed position since the center of action of the spring 99 is moved about the center line 94—107 upon movement of the handle to closed position.

In order to prevent this partial closing of the contacts by improper operation of the handle, a modified form of the invention comprising a latch 153 (Fig. 9) is provided in place of the latch 129 of the original embodiment. The latch is pivoted on the pivot 121 and a spring 154 urges the latch 153 in a counter-clockwise direction about its pivot to latching position. With the contacts and the operating handle in the closed circuit position the latch 153 is restrained in its ineffective position by the toggle pin 93, which thus assumes a position above the latch at a point indicated at 157 (Fig. 9). When the breaker is automatically tripped in response to an overload current in one of the poles, the toggle collapses as previously described and the pin 93 moves to the position in which it is shown in Fig. 9. As the pin clears the shoulder of the latch 153, the spring 154 rocks said latch counter-clockwise to the latching position shown wherein it is effective to prevent movement of the movable contact assembly toward closed position.

Since the latch 153 is not under the direct control of the handle 25 and the operating member 23, movement of these parts to closed position will not displace the latch 153 from its effective position. When the handle 25 and the operating member 23 are moved to the open position (Fig. 5) to reset the mechanism, the carrier 105 is rocked counter-clockwise to the position shown in Fig. 5, moving the toggle 83—84 to its completely collapsed position. At this movement the toggle link 63 rocks clockwise about the pin 93 from the position shown in Fig. 9 to that in which it appears in Fig. 5. During this movement a member 156 (Fig. 9) secured to the inner face of the yoke 92 of the toggle link 63 engages a projection 159 on the latch 153 and rocks the latch clockwise to its ineffective or unlatched position. When the operating member 23 is now moved to the closed position to close the contacts, the spring 99 moves above the center line 94—107 and attempts to straighten the toggle 83—84. Since the latch 119 at this time is in its latching position the movement of the toggle will be arrested by the pin 93 striking the roller 123. During the first part of the closing movement of the handle, the spring 99 moves the toggle a slight distance to take up the clearance between the pin 93 and the latch 119, and since the latch 153 is longer than the latch 119 the pin 93 passes above the latch 153 onto the surface 157 thereof so that the latter is held in its unlatched position and does not now prevent closing the breaker. The movable contacts will be released for closing movement by the spring 99 as previously disclosed, by the shoulder 127 moving the latch 119 to its ineffective position as the operating member 23 approaches its closed position. The spring 99 then closes the contacts as previously set forth.

From the above description it is clear that the latch 153 of the modification has the additional function of holding the movable contacts in full open position until the handle has been properly operated to reset and reclose the breaker.

Having disclosed several embodiments of the invention in accordance with the patent statutes, it is to be understood that various changes and

modifications may be made in the structural details disclosed without departing from some of the essential features of the invention. It is, therefore, desired that the invention be interpreted as broadly as the prior art permits, and that it is limited only by what is expressly stated in the following claims.

We claim as our invention:

5. A circuit breaker comprising relatively movable contacts, operating mechanism therefor including an operating member movable to open and to close said contacts, a member movable in response to predetermined abnormal conditions in the circuit to cause automatic opening of the contacts irrespective of the position of said operating member, said mechanism being resettable following automatic opening of said contacts, and latch means pivoted on a fixed support and operable to lock said contacts open upon automatic opening thereof while the operating member is held in closed position and until after said mechanism has been reset.
10. 2. A circuit breaker comprising relatively movable contacts, operating mechanism therefor including an operating member movable to open and to close the contacts, means releasable to cause automatic opening of the contacts, said means being resettable by a predetermined movement of the operating member, and latch means pivoted on a fixed support and operable to lock the contacts open upon automatic opening thereof while the operating member is held in closed position and until after the mechanism has been reset.
15. 3. A circuit breaker comprising relatively movable contacts, a resettable operating mechanism therefor including an operating member movable to open and to close the contacts, an operating toggle, an overcenter spring connecting said operating member and said toggle, means supporting one end of the toggle and releasably to cause automatic opening of the contacts, and latch means pivoted on a fixed support and operable to engage a part of said toggle to lock the contacts open upon automatic opening thereof while the operating member is held in closed position and until after the mechanism has been reset.
20. 4. A circuit breaker comprising relatively movable contacts, operating mechanism therefor including an operating member movable to open and to close the contacts, a member movable in response to predetermined abnormal conditions in the circuit to cause automatic opening of the contacts irrespective of the position of said operating member, said mechanism being resettable following automatic opening of the contacts, latch means pivoted on a fixed support and operable to lock the contacts open upon automatic opening thereof while the operating member is held in closed position and until after the mechanism has been reset, and another latch means operable to lock the contacts open upon opening thereof and until the operating member is moved a predetermined distance in a closing direction.
25. 5. A circuit breaker comprising relatively movable contacts, operating mechanism therefor including an operating member movable to cause opening or closing of said contacts and including a member movable from one position to a second position in response to predetermined conditions to cause automatic opening of the contacts irrespective of the position of the operating member, said mechanism being resettable by a predetermined movement of said operating member following automatic opening of said contacts, means

mounted for movement independently of said mechanism and engageable with a part movable with the contacts for automatically locking said contacts in open position upon automatic opening thereof while the operating member is held in closed position, and until said mechanism has been reset.

6. A circuit breaker comprising relatively movable contacts, operating mechanism therefor including an operating member movable to open and closed positions to cause opening and closing of the contacts, a member movable from one position to a second position in response to predetermined conditions to cause automatic opening of the contacts irrespective of the position of the operating member, and means mounted for movement independently of said mechanism and engageable with a part movable with the contacts for locking said contacts open upon automatic opening thereof while the operating member is held in closed position and until the operating member is moved a predetermined amount toward open position.

7. A circuit breaker comprising relatively movable contacts, operating mechanism therefor including an operating member movable to open and closed positions to cause opening and closing of the contacts, a member movable from one position to a second position in response to predetermined condition to cause automatic opening of the contacts irrespective of the position of the operating member, and means mounted for movement independently of said mechanism and engageable with a part movable with the contacts for locking the contacts open upon automatic opening thereof while said operating member is held in closed position and until the operating member is moved to its full open position.

8. A circuit breaker comprising relatively movable contacts, operating mechanism therefor including an operating member movable to open and closed positions to cause opening and closing of the contacts, a member movable from one position to a second position in response to predetermined conditions to cause automatic opening of the contacts irrespective of the position of the operating member, and means mounted for movement independently of said mechanism and engageable with a part movable with the contacts for locking said contacts in open position upon automatic opening of said contacts as long as the operating member is within a predetermined distance of the closed position.

9. A circuit breaker comprising relatively movable contacts, operating mechanism therefor including an operating member movable to open and close the contacts, a member movable in response to predetermined abnormal conditions in the circuit to cause automatic opening of the contacts irrespective of the position of said oper-

ating member, said mechanism being resettable by a predetermined movement of said operating member after automatic opening of said contacts, and a pair of coaxially pivoted latch members engageable with a part movable with the movable contacts, one of said latch members being operable to automatically lock the contacts open upon automatic opening thereof and until said operating member is moved a predetermined amount in an opening direction, the other of said latch members being operable to lock the contacts open upon automatic opening thereof until the operating member is moved a predetermined distance in a closing direction.

10. A circuit breaker comprising relatively movable contacts, operating mechanism therefor including an operating member movable to cause opening or closing of said contacts and including a member movable from one position to a second position in response to predetermined conditions to cause automatic opening of said contacts, and a latch movable independently of said mechanism and engageable with a part movable with the contacts for automatically locking said contacts in full open position upon automatic opening thereof, said latch being effective to lock said contacts open as long as said operating member remains in closed position or in proximity to closed position after automatic opening of said contacts.

11. A circuit breaker comprising relatively movable contacts, operating mechanism therefor including an operating handle movable to an open position and to a closed position to open and close said contacts, and a member movable in response to predetermined abnormal circuit conditions to cause automatic opening of the contacts irrespective of the position of the operating handle, said operating mechanism being resettable following automatic opening of the contacts, and latch means pivoted on a fixed support and operable to lock said contacts open upon automatic operation thereof while the handle is held in closed position.

12. A circuit breaker comprising relatively movable contacts, operating mechanism for said contacts including an operating handle movable to open and closed positions to cause opening and closing of the contacts, a member movable from one position to a second position in response to predetermined conditions to cause automatic opening of the contacts irrespective of the position of the operating handle, and means mounted for movement independently of said mechanism and engageable with a part movable with the contacts for locking the contacts open upon automatic opening thereof while the handle is held in closed position.
